PLURAL - STAGE STONE - CRUSHING MILL
WITH INDEPENDENT AND ARCUATELY
SWINGABLE JAWS

James L. Brickley, Spokane, Wash.

Application January 23, 1948, Serial No. 3,921

3 Claims. (Cl. 241—148)

1

This invention relates to mills designed for breaking or crushing materials such as stones or the like, eliminating the use of jaws which grind the rock, and which are short lived, owing to the severe abrasive action which takes place between the jaws during the crushing operation.

An important object of the invention is to provide a mill including a plurality of swinging hammer arms on which superposed hammers are mounted, together with means for swinging the arms and hammers against material delivered therebetween, the construction of the arms and hammers being such that a combined hammer action and grinding action takes place as the hammers swing.

Another object of the invention is to provide a machine which will permit the elimination of particles of finished product as soon as they are formed, thereby preventing the accumulation of finished material forming a so-called cushion to retard and hamper the milling operation of the unfinished material.

Still another object of the invention is to provide a mill structure which may be readily and easily knocked down or dismantled to facilitate transportation and the ready assembly of the device when delivered at the point of operation.

With the foregoing and other objects in view which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

Referring to the drawings:

Figure 1 is a side elevational view of a machine constructed in accordance with the invention.

Fig. 2 is a plan view thereof.

Fig. 3 is a sectional view taken on line 3—3 of Fig. 2.

Fig. 4 is a sectional view taken on line 4—4 of Fig. 3.

Fig. 5 is a sectional view taken on line 5—5 of Fig. 3.

Fig. 6 is a sectional view taken on line 6—6 of Fig. 2.

2

Fig. 7 is a perspective view of one of the swinging hammers, forming a part of the invention.

Fig. 8 is a perspective view of one of the cups of the elevator wheel.

Referring to the drawings in detail, the mill comprises a body portion or frame including a base indicated generally by the reference character 5 to which the sheet metal side members 6 of the body portion are secured, the upper ends 10 of the sheet metal side members being held in spaced relation with respect to each other, by means of the cross bars 7 disposed adjacent to the ends of the side members.

The sheet metal side members are formed with 15 outwardly disposed longitudinal flanges at the upper edges thereof, the flanges being indicated by the reference character 8, and to these flanges are secured bearings 9 that are bolted in position by means of the bolts 10. Transversely disposed 20 shafts 11 have their ends mounted in the bearings 9, and provide supports for the hanger arms 12 which are mounted on the shafts 11, adjacent to the ends thereof, the arms 12 providing supports for the hammers 13 which embody heavy 25 weighted members, the heavy weighted members in the present showing comprising long metal bars 14 provided with hard steel caps 15 that completely house the side faces of the long metal bars, providing wear surfaces to contact the stone or rocks being treated.

As clearly shown by Fig. 3 of the drawings, these hammers are arranged one above the other, and are three in number, although the number of hammers supported on the hanger arms, may be varied to meet various requirements.

The hammers are arranged in parallel spaced relation with respect to each other and are so mounted that they will swing freely towards and away from each other, with the result that stones or material passing between adjacent hammers, will be crushed by the blows of the hammers moving towards each other.

In the construction of the steel caps, extensions 16 are provided that extend inwardly over the upper and lower surfaces of the long metal bars and through which connecting rods 17 extend, securing the caps to the bars 14.

As shown, the hammers are five in number,

to the center of which are attached arms 18, the operating arms 18 or connection between the central hammer and operating arms being at the ends of the lowermost hammer element of the central hammer, as shown by Fig. 3 of the drawings.

These operating arms have their rear ends connected by means of the transverse bar 19 that has spaced bearing ears 20 between which the arm 21 is pivotally mounted, the arm 21 being pivotally connected to the lower end of the link 22 that in turn has pivotal connection with the pitman 23 that is pivotally connected with the shaft 24 mounted on the main frame 25 forming a part of the power element of the mill.

The rear end of the pitman 23 connects with the link 26 that in turn is connected with the crank arm 27 secured to the shaft 28 mounted within the bearings 29 on the ends of which are mounted balance wheels 30. Mounted on one end of the shaft 28, is a pulley 31 over which the belt 32 operates, the belt also moving over a suitable power pulley operating as a part of a power plant not shown, for transmitting rotary movement to the shaft 28.

Thus it will be seen that due to this construction, when the shaft 28 rotates, the center hammer will be rocked forwardly and rearwardly. As the center hammer moves forwardly, material deposited between adjacent hammers will be broken by the hammers moving towards each other. As the central hammer moves rearwardly, the stones and material deposited between these hammers will be crushed by the action of the hammers moving towards each other.

The side members 6 are connected at a point intermediate their upper and lower edges, by means of the bar 33, which bar is provided with openings through which the bolts 34 move, the bolts 34 providing supports for the coiled springs 35 that also bear against the bar 36. These springs and bars 33 and 36 provide a stop of a yieldable character, and against which the adjacent hammer engages as the hammers at this side of the central hammer move rearwardly.

Pivotaly supported on bearings that extend inwardly from the side members 6, are hanger rods 37 that have their lower ends extended through openings in the movable trough 38, the rods 37 having threaded ends 39 on which the nuts 40 operate whereby the angle of operation of the trough 38 may be regulated. This trough 38 hangs directly under the hammers, and extends throughout the width of the body portion of the mill to receive material which has been crushed between the hammers, as the material falls from the hammers.

Extending forwardly from the front hammer are arms 41 that are in alignment with the hanger rods 37 at the front end of the machine, so that as the hammers move forwardly, these arms 41 will engage the hanger rods disposed adjacent thereto, moving the hanger arms and trough supported thereby to shake the trough 38 and feed material to the lower end thereof.

Extending into the upper portion of the body, is a feed trough 42, to which material from the spout 43 is delivered, the material passing over the feed trough 42 onto the hammers 13.

Directly in front of the discharge end of the trough 38, is a platform 44 which is inclined towards the trough 45, so that material fed onto the platform 44 from the trough 38, will be directed into the trough 45.

Secured to the base, and rising therefrom, are supports 46 which have the bearing 47

mounted on the upper end thereof, the bearing 47 providing the bearing for the shaft 48 on which the elevator wheel 49 is secured to operate therewith.

The elevator wheel is of a construction so that the cups 50 thereof extend forwardly from the ring 51, the cups moving in a circle around the extended end 52 of the trough 42. Thus it will be seen that as the elevator wheel operates through the trough 45, material will be picked up by the cups 50 and deposited on the extended end 52 of the trough 42 where the material will by gravity, feed to the upper surfaces of the hammers which being in motion, will crush the material between the adjacent faces of the hammers, as the hammers are moved towards each other.

A pulley indicated by the reference character 53 is secured to one end of the shaft 48 and receives its motion from a suitable power device not shown, through the belt 54.

In the operation of the mill, coarse mesh rock is fed through the spout 43 of the feed hopper, onto the feed trough 22, from where the rock is delivered onto the upper ends of the hammers 13.

As the hammers are moved into and out of contact with each other rapidly, the rock falling between adjacent hammers is crushed between the hammers and falls into the trough 38. As the trough is reciprocated by the action of the hammers, the material is fed into the trough or sump 45, where it is picked up and carried onto the feed trough 42 for further crushing.

With this mill, coarse mesh rock or material will be reduced to the desired grade with the minimum amount of wear on the mechanism of the mill.

Having thus described the invention, what is claimed is:

1. A rock crushing mill comprising a body portion, a row of depending independent vertical swinging arms mounted on the body portion in horizontal spaced relation with respect to each other, a plurality of superimposed vertically spaced hammers mounted on each arm, the hammers of adjacent swinging arms being spaced apart, operating arms connected with the lowermost hammer of the intermediate arm of the row of hammers, whereby said hammers are moved into crushing relation with each other as the operating arms reciprocate, crushing stones delivered therebetween, and means for delivering stone to the spaces between adjacent hammers.

2. A rock crushing mill comprising a body portion, a row of horizontally disposed shafts supported on the body portion, a row of depending swinging arms mounted on the shaft, rows of superimposed hammers spaced apart and secured to the arms at points below the pivot points of the arms, the hammers being disposed in vertical spaced relation with respect to each other, operating arms connected with the lowermost hammer of one of said arms, means for reciprocating the operating arms moving the hammers of adjacent arms into crushing relation with respect to each other, and means for cushioning the movements of the swinging arms.

3. A rock crushing mill comprising a body portion, a row of horizontally disposed shafts supported by the body portion, a row of depending swinging arms mounted on the shafts, superimposed hammers secured to the arms below the pivot points of the arms, said hammers being disposed in vertical spaced relation with respect to each other, operating arms connected with one

of said hammers, and means for reciprocating the operating arms moving the swinging arms and hammers crushing material delivered between the hammers of the swinging arms.

JAMES L. BRICKLEY. 5
